(57) **CLAIM**

The ornamental design for a cane, as shown and described.

DESCRIPTION

FIG. 1 is an isometric view of the cane.

FIG. 2 is another isometric view of the cane in FIG. 1.

FIG. 3 is a right side view of the cane in FIG. 1.

FIG. 4 is a left side view of the cane in FIG. 1.

FIG. 5 is a front view of the cane in FIG. 1.

FIG. 6 is a rear view of the cane in FIG. 1.

FIG. 7 is a top view of the cane in FIG. 1.

FIG. 8 is a bottom view of the cane in FIG. 1.

FIG. 9 is an isometric view of the cane with a different set of unclaimed features.

FIG. 10 is yet another isometric view of the cane in FIG. 9.

FIG. 11 is a right side view of the cane in FIG. 9.

FIG. 12 is a left side view of the cane in FIG. 9.

FIG. 13 is a front view of the cane in FIG. 9.

FIG. 14 is a rear view of the cane in FIG. 9.

FIG. 15 is a top view of the cane in FIG. 9; and,

FIG. 16 is a bottom view of the cane in FIG. 9.

The broken lines depict boundaries of the claim and portions of the article that form no part of the claimed design.

1 Claim, 8 Drawing Sheets
